FOLDABLE HOIST

Kibbey W. Couse, Newark, N. J.

Application April 30, 1952, Serial No. 285,262

1 Claim. (Cl. 212—8)

My invention relates to a foldable hoist and has as its prime object the provision of a foldable hoist having a boom which is swingable from one side of its supporting structure to a horizontal or nested position on the other side of the supporting structure and wherein the supporting structure for the boom is swingable to a horizontal or nested position opposite from that of the boom.

It is another object of my invention to provide a foldable hoist wherein the mechanism for operating the boom and for lifting loads carried by the boom may be operated by a small portable tool from a single location and by one man.

It is another object of my invention to provide a foldable hoist of the described type in which the operating mechanism is provided with means for holding such mechanism against the weight of the boom and any loads carried by it with the power disconnected.

Other objects and advantages of my invention will become apparent as the course of the specification progresses.

To attain the objects and advantages of my invention, I provide a foldable hoist having a boom and a supporting structure for the boom both of which are pivotally mounted in a fixed location at corresponding ends. The boom is swingable about its pivotal axis from one side of the supporting structure in its normal operating position to a horizontal or nested position on the other side, and the supporting structure is itself swingable about its pivotal axis with the boom in its nested position from the normal operating position to a horizontal position opposite from that of the boom. Suitable mechanism is provided for operating the boom and for raising and lowering any load carried by the boom. This mechanism is adapted for operation by a portable hand tool and incorporates a worm and gear wheel drive for holding the mechanism against the weight of the boom and any load carried by the boom with the power removed.

I shall describe one form of my invention and point out the novel features thereof in claim.

In the accompanying drawings, Fig. 1 is a perspective view of the foldable hoist showing the boom being raised on one side of the supporting structure.

Fig. 2 is a perspective view of the foldable hoist with the boom being lowered on the other side of the supporting structure.

Fig. 3 is a perspective view of the foldable hoist with the boom in its nested position and with a supporting structure being lowered into a horizontal position opposite from the boom.

Figs. 4 through 9 are side elevational views of the foldable hoist showing the boom in progressive stages of its operation from one side of the supporting structure to a nested position on the other side and showing the supporting structure being operated to its horizontal position with the boom in its nested position.

Fig. 10 is a top plan view of the boom and supporting structure in their horizontal positions with the block and tackle gear removed.

2

Referring to the drawings, reference character 1 designates a V-shaped boom comprising members 2 and 3 converging at one end and diverging at the opposite end of the boom. The diverging ends of members 2 and 3 are pivotally connected at 4 to a base plate 5 which is shown secured to foundation 6. Also pivotally connected at 4 to base plate 5 is a supporting frame 7 which is secured in a normal operating position by brace members 8 which are pivotally connected to foundation 6 and to opposite sides 9 and 10 of supporting frame 7. Boom 1 is swingable about its pivotal axis from one side of supporting frame 7 in its normal operating position over and about the supporting frame to a horizontal position on its other side.

Supporting frame 7 has a windlass 51 mounted thereon for raising and lowering the boom, which windlass comprises a drum 20 rotatably mounted in frame 7, a gear wheel 21 operatively connected to drum 20, and a worm gear 22 positioned for coaction with gear wheel 21. The windlass is connected with boom 1 by suitable block and tackle gear comprising a line 23 which is secured to drum 20, a block pulley 24 pivotally connected at 25 to a triangular shaped plate 26 which is pivotally mounted at the diverging ends of boom 1, and a block pulley 27 which is pivotally connected to members 28 which in turn are pivotally connected to opposite members 9 and 10 of frame 7. Line 23 extends from drum 20 over block pulley 24 and over block pulley 27 back to pulley 24 where it is finally secured, and to be connected to the boom. Boom 1 is raised by rotating drum 20 in a clockwise direction as viewed in Figs. 4 through 9 and is lowered when drum 20 is rotated in a counterclockwise direction. Worm gear 22 is provided with a male fitting 29 which is adapted to rotate the worm gear. The aforesaid windlass for controlling boom 1 may be operated by portable drill 30 having a recessed fitting 31 secured thereon suitable for engaging male fitting 29. Portable drill 30 should be provided with a reversible motor so that it may be operated in one direction to raise boom 1 and operated in the opposite direction to lower boom 1. Portable drill 30 may be of the pneumatic type as shown in the drawings in which event it will be connected by a suitable air hose 32 to a source of compressed air.

In operating boom 1 from one side (Fig. 4) to a horizontal or nested position on the other side (Fig. 8) portable drill 30 is caused to rotate in a clockwise direction as viewed in Figs. 4 and 5. Drum 20 responds by also rotating in a clockwise direction whereupon boom 1 is caused to raise. When boom 1 attains a vertical position the motor in portable drill 30 is reversed to provide for the lowering of boom 1. To initiate the lowering of boom 1, a slight force is imparted to the boom to move it beyond its vertical position. Secured to supporting member 7 at the upper ends of opposite members 9 and 10 is a bar 40 which has a wheel 41 slidably mounted thereon. When boom 1 is operated to its other side (Figs. 6, 7 and 8) boom line 23 rides on wheel 41.

Supporting frame 7 is provided with another windlass 52 comprising drum 42, gear wheel 43, and worm gear 44. Drum 42 has a line 45 wound thereon which line extends over a pulley 46 which is pivotally mounted at 50 upon triangular plate 26. Line 45 is provided at the end thereof with the usual type of lifting hook 47. Worm gear 44 is provided with a male fitting 48 which is adapted for engagement by the recessed fitting 31 secured upon portable drill 30, thus enabling portable drill 30 to operate both windlasses. When drum 42 is caused to rotate in a clockwise direction (Figs. 4 to 9) lifting hook 47 and any load to which it is secured is caused to move upwardly. When drum 42 is moved in a counterclockwise direction, hook 47 and any load to which it might be attached is moved downwardly. When boom 1 is moved

from one side as viewed in Figs. 4 and 5 of supporting frame 7 to its other side as viewed in Figs. 6 and 7 with boom 1 from the one side of supporting frame 7 to its other side, the hook and load remaining in a vertical position at all times. Windlass 52 is of course operable with the boom on its other side to raise and lower lifting hook 47. Boom 1 may have a plurality of engaged floodlights 48 secured at its converging ends which are directed in the direction of hook 47. Floodlights 48 are connected in the usual manner through suitable conduits encased within members 2 and 3 to pigtailed 49.

As already noted, supporting frame 7 is pivotally connected at 4 to base plate 5 which is secured upon machine shop floor 6. It has also been noted that supporting frame 7 is secured in a normal operating position by brace members 8 which are connected both to the supporting frame and to foundation 6. When boom 1 is operated to a horizontal position on its other side (Fig. 8), brace members 8 are disconnected from supporting frame 7 to permit supporting frame 7 to be pivoted to the left as viewed in Fig. 8. In this connection, it is to be noted that supporting frame 7 is capable only of being pivoted in one direction, namely to the left as viewed in Fig. 8, the lower end of supporting frame 7 being especially formed for this purpose. The lower end of frame 7 accordingly has a rounded end formed on one side and a square end on its other side. If drum 20 of windlass 51 is rotated in a counterclockwise direction as viewed in Fig. 8 after boom 1 has attained its horizontal or nested position, supporting frame 7 is caused to pivot in a counterclockwise direction as viewed in Fig. 8 until it attains a horizontal position opposite from that of boom 1 (Fig. 9). Boom 1 is of sufficient weight to permit the supporting frame 7 to be lowered from its normal operating position to its horizontal operating position without moving boom 1 from its nested position.

It will now be apparent that I have provided a foldable hoist having a boom and supporting structure for the boom and wherein the boom may be operated from one side of the supporting structure to a horizontal or nested position on the other side of the supporting structure and wherein the supporting structure may be operated to a horizontal position opposite from the boom after the boom has attained its nested position. It will be apparent also that my foldable hoist may be operated by a small portable drill or even by a hand crank from a single location and by one man, and that because of the worm and gear wheel driving mechanism incorporated into each windlass both the boom and any load carried thereby will

be maintained in the positions to which they have been operated until intentionally moved therefrom.

Although I have herein shown and described only one form of my invention, it is to be understood that various changes and modifications may be made therein within the scope of the appended claim without departing from the spirit and scope of my invention.

What I claim is:

In a foldable hoist, the combination of a base, a boom comprising spaced members, a supporting frame for the boom pivotally mounted at one end on the base between said spaced members of the boom, means separably connected to the supporting frame for securing the supporting frame in a normal vertical operating position, the boom members being pivotally mounted at one end on said base and the boom being swingable about its pivotal axis from a hoisting position at one side of the supporting frame about and over the supporting frame to a horizontal position on the opposite side of the frame, the supporting frame being swingable about its pivotal axis from its vertical normal operating position to a horizontal position opposite to the boom when the latter is horizontal, a windlass mounted on said supporting frame, and gear including a cable and pulleys connecting the windlass to the boom for raising and lowering the boom while the boom is at either side of the vertical supporting frame and for lowering the supporting frame to its horizontal position with the boom in its horizontal position, said gear including a cable guide mounted on said supporting frame between said windlass and the free end of said supporting frame to guide said cable around the end of said supporting frame when the boom is in the second-mentioned position, there being included in said gear a pulley connected to said boom, a second pulley connected to said supporting frame between said windlass and the free end of said supporting frame, said cable having one end connected to said boom and its other end connected to said windlass with the intermediate portions of the cable passing from said windlass around the first-mentioned pulley and thence around the second mentioned pulley to said boom when the boom is in the first-mentioned position, and said cable also passing around said cable guide when the boom is in the second-mentioned position.
